CLAIM

The ornamental design for a pump filter part as shown and described.

DESCRIPTION

FIGS. 1 and 2 are bottom perspective and bottom plan views, respectively, of an outer pump filter part in accordance with a second embodiment of our design; and, FIGS. 3 and 4 are bottom perspective and bottom plan views, respectively, of a portion of the outer pump filter part of FIGS. 1-2.

The pump filter parts shown in broken lines in the figures depict unclaimed environmental subject matter, are for illustrative purposes only, and form no part of the claimed design. Similarly, unshaded portions that appear between broken lines or beyond boundary or break lines in the figures form no part of the claimed design.
